UNITED STATES PATENT OFFICE.

OSCAR WIEDERHOLD, OF JERSEY CITY, NEW JERSEY.

HOLDER FOR INCANDESCING MANTLES.

No. 811,018.

Specification of Letters Patent.

Patented Jan. 30, 1906.

Application filed March 7, 1905. Serial No. 249,143.

To all whom it may concern:

Be it known that I, OSCAR WIEDERHOLD, a citizen of the United States, residing in Jersey City, in the county of Hudson and State 5 of New Jersey, have invented certain new and useful Improvements in Holders for Incandescent Mantles, of which the following is a specification.

This invention relates to holders for mantles of incandescent material, such as are ordinarily used in connection with gas-burners, and aims to provide an improved holder especially but not exclusively for mantles which are suspended and hang down from the gas 10 burner or tip. This arrangement of mantles is especially useful in connection with Pintsch gas-burners as used on railway-trains, for example. Prior to this invention the life of such mantles has been short. It has been 15 found that the mantle soon breaks along the upper edge or becomes expanded to such extent as to slip off the ring upon which the upper edge is usually fastened, either event terminating the usefulness of the mantle. This 20 destruction or enlargement of the upper edge 25 of the mantle is probably due to the accumulation of paraffin or other oily matter which is applied to the mantle to enable it to bear transportation and which is burned off at the beginning of use. The oily matter accumulates at the upper edge against the supporting-ring, where it does not burn away immediately, but boils so as to break the very weak material of the mantles. At the same time 30 the upper edge of the mantle is enlarged, and with the lubrication provided by the oily 35 matter easily slips off the ring.

According to the present invention as large a portion as possible of the upper edge of the 40 mantle is left free, so as to permit the ready burning away of the oily matter, the mantle being supported upon a series of points spaced apart from each other for this purpose. The supporting of the edge of the mantle at a series 45 of separate points instead of upon a continuous ring also permits enlargement of the edge of the mantle without disengagement, the increased length of the edge being taken up by sagging between the points of support. 50 It is customary to first burn out the cotton and then harden the mantles in their final shape by baking them after they are tied upon the holders. With the old ring-shaped holder the edge of the mantle is protected on one 55 face from the action of the hardening-flame,

and is therefore weaker than the rest of the mantle. The mantle therefore fails very quickly in use, as the part which has to hold the weight is the weakest. The hardening-flame, with my improved holder, has substantially or nearly equal access to both faces of the mantle at the edge as well as throughout the body, and consequently the edge is substantially as well hardened as the remainder of the mantle. Certain other advantages are referred to in detail hereinafter.

The accompanying drawings illustrate an embodiment of the invention.

Figure 1 is an elevation of a burner with the parts pertaining to this invention in section. Fig. 2 is an elevation of the mantle and holder, showing its appearance after it has been in use. Fig. 3 is an elevation of a different holder.

Referring to the embodiment illustrated, A 75 is the gas-tip, through which flows gas or a mixture of gas and air or gas and oxygen by any usual or suitable arrangement.

B is a mantle, preferably in the shape of a small bag with an open end. The mantle is 80 supported in suitable position below the tip from a mantle-holder C. In order to provide a series of points of support spaced apart from each other, the holder is provided with a series of depending fingers D, spaced apart 85 from each other as far as possible, the spacing being limited by the fact that there must be a sufficient number of fingers to maintain the horizontal shape of the mantle, and the fingers must be of sufficient width to have the 90 required strength and resistance to heat. Preferably the holder is formed of so-called "lava" or other refractory material. The edge 95 of the mantle is reinforced by means of a cord E of asbestos or other refractory material passed back and forth through the edge. The holder C, however, may be formed of metal, as illustrated in Fig. 3, in which case the fingers D' may be of wire much smaller than the fingers D of lava, and therefore giving even 100 fuller access of the inner face of the edge of the mantle to the baking-flame.

With the described arrangement it will be seen that substantially or nearly all the edge F of the mantle is free, so that the coating 105 ordinarily applied to strengthen the mantle for transportation can burn off immediately and without bubbling or other disturbance. The fingers D or D' are made as narrow as possible, so that there can be no substantial 110

accumulation of the coating material against them. At the same time the edge of the mantle as it expands may sag more or less between the fingers, as indicated in Fig. 2, so as to retain its hold upon the ends of the fingers.

For hooking or attaching the edge of the mantle upon the ends of the fingers D they may be formed with horizontal grooves G, into which the asbestos cord E fits, the ends of the cord being tied after the mantle is applied to the holder. It is understood that the mantle and holder are attached at the factory and sold in this form.

15. The holder C is preferably attached to the tip A by screwing it upon the same, though any suitable means of attachment may be used. The upper portion of the holder is preferably in the form of a comparatively wide flat ring 20 H, which serves to deflect the hot gases and prevent overheating of the upper portion of the burner. At the same time the fingers D are preferably made of such length as to permit the escape of the products of combustion from 25 the tip to the outside of the mantle, so as to avoid clogging the burner. The holder may be screwed to a higher or lower point on the tip, so as to adjust the level of the mouth of the tip relatively to the edge of the mantle 30 to get the best results. This arrangement of a space between the ring H and the edge of the mantle and the capability of adjusting the height of the holder and mantle are of especial value in connection with an upright burner. 35 Certain other features also may be used with advantage in connection with upright burners, giving a very rigid and durable mantle.

Though I have described with great particularity of detail a certain specific embodiment of the invention, yet it is not to be understood that the invention is limited to the exact embodiment described. Various modifications thereof in detail and in the arrangement and combination of the parts may be 45 made by those skilled in the art without departure from the invention.

What I claim is—

1. In combination a ring and a mantle attached thereto with its edge spaced apart from the ring to permit the escape of products of combustion.

2. A holder for mantles adapted for attachment to a mantle and adapted to screw on the end of a gas-tip, whereby the mantle is held rigidly on the tip and is adjustable in height. 55

3. In combination, a mantle-holder for depending mantles and having a plurality of depending fingers, and a mantle depending from said holder and having its upper edge held against the lower ends of said depending fingers whereby it is supported and held from collapsing inward by said fingers. 60

4. A holder for depending mantles having a ring adapted to be fastened on the gas-tip, and a plurality of depending fingers the ends of 65 which are adapted to engage and support the mantle.

5. In combination, a holder having a plurality of points of suspension spaced apart from each other, and a mantle attached to the 70 holder by a cord passing around and holding the edge of the mantle against said points.

6. In combination a ring and a mantle suspended with its upper edge a distance below said ring, spaces being left between said ring 75 and the edge of the mantle for the escape of products of combustion.

7. A holder for depending mantles having a plurality of depending fingers D, the lower ends of which are provided with grooves G 80 for holding the edge of the mantle, and which are spaced apart from each other, and having a ring H at the upper end adapted to deflect the gases downward, said holder having a provision for fastening it on a gas-tip. 85

In witness whereof I have hereunto signed my name in the presence of two subscribing witnesses.

OSCAR WIEDERHOLD.
